UNITED STATES PATENT OFFICE.

IVAN HANKOVICH AND WINKO HANKOVICH, OF EAST CHICAGO, INDIANA.

RAIL TIE AND FASTENER.

1,216,989.

Specification of Letters Patent Patented Feb. 20, 1917.

Application filed October 19, 1916. Serial No. 126,579.

To all whom it may concern:

Be it known that we, IVAN HANKOVICH and WINKO HANKOVICH, subjects of the King of Hungary, residing at East Chicago, in the county of Lake and State of Indiana, have invented certain new and useful Improvements in Rail Ties and Fasteners, of which the following is a specification.

This invention relates to certain new and useful improvements in rail ties and fasteners.

The primary object of the present invention is to provide an improved form of rail tie and fastener in which the tie is of channel formation and is adapted to receive longitudinally sliding rail supporting blocks whereby the exact gage of the track may be obtained with the rails positioned at desired distances from either end of the tie.

A further object of the invention is to provide an improved form of rail tie and fastener in which the rail is held slightly elevated from the tie proper with sliding blocks carrying cushioning elements upon which the rails are seated, slidably positioned in the tie.

A still further object of the invention is to provide a rail tie of channel formation with sliding blocks positioned therein for the support of the rails with independently operating means for shifting the outwardly positioned rail supporting blocks and a single device for simultaneously shifting the inwardly positioned blocks with means associated with the last named means for holding the inwardly positioned blocks in adjusted positions.

With the above general objects in view and others that will appear as the nature of the invention is better understood, the same consists in the novel construction, combination and arrangement of parts to be hereininafter more fully described and then claimed.

In the accompanying drawings forming a part of this application and to which reference is had herein by like characters designating corresponding parts throughout the several views:

Figure 1 is a cross sectional view of a rail track showing in elevation the improved tie and showing in section the rails supported thereon.

Fig. 2 is a top plan view of one of the ties with rails positioned therein.

Fig. 3 is a longitudinal sectional view taken on line III—III of Fig. 2 showing the rail supporting blocks and the adjusting means therefor.

Fig. 4 is a cross sectional view taken on line IV—IV of Fig. 1 showing in elevation the outer rail supporting block.

Fig. 5 is a cross sectional view taken on line V—V of Fig. 3 showing in section the outer rail supporting block, and in full lines the cushioning strip for supporting the rail.

Fig. 6 is a cross sectional view taken on line VI—VI of Fig. 3 showing the locking arms carried by a cover plate associated with the rail tie for preventing movement of the shifting arms for the inwardly positioned rail supporting blocks.

Fig. 7 is a cross sectional view taken on line VII—VII of Fig. 3 showing the rail supported on the cushion blocks and spaced from the upper edges of the tie.

Fig. 8 is a perspective view of one of the rail supporting blocks, and

Fig. 9 is a detail perspective view of one of the rail ties partially broken away and showing the structure of the inner walls thereof.

Referring more in detail to the accompanying drawings, the reference numeral 10 designates in general the rail supporting tie upon which the rails 11 are mounted and retained in such position by the outwardly positioned rail supporting blocks 12 and the inwardly positioned rail supporting blocks 13, while a spacing plate 14 is supported on the upper edges of the tie 10 between the inwardly positioned rail supporting blocks 13 as is clearly shown in Figs. 1 and 2.

The improved form of rail tie 10 is shown more clearly in detail in Fig. 9 and includes side walls 15 and end walls 16, the tie being open at its upper side as is illustrated to be of channel formation. The inner faces of the side walls 15 of the tie are inclined inwardly and upwardly as at 17 from the bottom wall thereof, while the intermediate portions thereof are provided with parallel vertical walls 18 opposing each other, and which parallel walls are provided with

notched portions 19 for purposes presently to appear. The upper edges of the opposite walls 15 of the tie adjacent each end thereof are provided with cut away portions 20 over which the rails 11 are adapted to be supported.

The rail supporting blocks 12 and 13 are of the form more clearly shown in Fig. 8 and each includes a flat bottom wall 21, 10 vertical end walls 22 and 23 and upwardly and inwardly inclined side walls 24. Each of the blocks 12 and 13 is provided with an enlarged head 25 which projects from all sides thereof, and the sides projecting 15 toward each other as shown more clearly in Fig. 3 constitute rail engaging flanges 26. The opposed edges 23 of the rail supporting blocks 12 and 13 are cut away at their upper sides as at 27 directly beneath the head 20 25 and rail engaging flange 26 to provide dove-tail seats 28 within which are mounted dove-tail blocks 29 of compressed fiber or other resilient material.

In positioning the rail supporting blocks 25 within the tie 10, the blocks 12 are first introduced thereto through the central space provided by the parallel walls 18 with the flanges 26 inwardly directed. When lowered into this position, the blocks may be 30 moved lengthwise of the tie with the inclined side walls 24 thereof engaging the inclined side walls 17 of the tie thereby preventing upward movement thereof and obviating accidental displacement. The rail 35 supporting blocks 13 are positioned in the channel ties in a similar manner with the rail engaging flanges 26 thereof directed outwardly and interlocked with the ties in a like manner. With the blocks 12 and 40 13 positioned as shown in Fig. 3 the base flanges of the rails 11 are seated on the blocks 29 and are slightly spaced upwardly from the cut away portions 20 in the opposite side walls 15 of the tie 10. This allows 45 for a cushioning movement of the rail during the passage of trains thereover.

Means is provided for holding the outer blocks 12 in locked engagement with the base flanges of the rails and includes a 50 wrench operated screw 30 passing through the opposite end walls 16 of the tie for engagement with the outer face 22 of the said block. By adjusting the screws 30, the blocks are moved into the desired position 55 and in locked engagement with the rails 11.

The mechanism for shifting the inwardly positioned rail supporting blocks 13 includes a longitudinally disposed rod 31 having one end threaded over a portion of its 60 length as at 32 and adapted for threaded reception in the threaded socket 33 provided in one of the blocks 13. The central portion of the rod 31 is provided with a rectangular portion 34 as more clearly shown

in Figs. 3 and 6, while the opposite end 65 of the rod is adapted to be received in a socket 35 provided in the face 22 of the co-operating block 13. A suitable wrench applied to the rectangular portion 34 of the rod 31 and permitted a limited movement 70 by the cut out portions 19 in the vertical portions 18 of the tie will cause the blocks 13 to move into positive engagement with the rails 11 with the flanges 26 thereof engaging the said rails.

In order to hold the blocks 12 and 13 in locked position by the rod 31, there is provided the spacing plate 14 which is adapted to be seated on the upper edges of the side walls 15 of the tie and be retained in such 80 position by fastening members such as screws or threaded bolts 36 passing therethrough and received in threaded sockets 37 provided in the upper edges of the said tie walls. Depending parallel arms 38 are 85 carried by the spacing plates 14 and with the spacing plates attached to the tie as shown in Figs. 3 and 6. The said arms straddle the rectangular portion 34 of the rod and lie juxtaposed thereto to prevent 90 relative rotary movement of the said rod whereby the rod and rail supporting blocks 13 are effectively locked in assembled position in the tie.

From the above detailed description of the 95 device, it is thought that the construction and operation thereof will be plainly obvious, it being noted that the cushion blocks 29 may be readily replaced when worn or otherwise damaged as well as the rail supporting blocks 12 and 13 which are comparatively inexpensive to manufacture.

While the construction shown is believed to be the preferable embodiment of the present invention, it is nevertheless to be understood that various changes in the construction may be made without departing from the spirit and scope of the invention 105 as claimed.

What we claim as new is:—

1. A device of the class described comprising a rail tie of channel formation including side walls, end walls and a bottom wall, the inner faces of the side walls being upwardly and inwardly inclined from the bottom wall, the central portions of the inclined faces of the side walls being vertically disposed with notches formed therein, rail supporting blocks having angularly disposed side walls received in said channel tie 115 through the central portion thereof and moved to a position whereby the inclined side walls thereof engage the inclined inner faces of the tie walls, enlarged heads carried by the rail supporting blocks, said 120 blocks being cut away on their opposed faces adjacent said heads, dove-tail sockets formed in the upper sides of said cut away portions,

5 cushion blocks received in said dove-tail sockets, rail engaging flanges carried by said blocks, a screw passing through each end wall of said tie adapted to engage the outer faces of the outwardly positioned blocks, a rod having threaded engagement with one of said inwardly positioned blocks and a loose engagement with the other one of said inwardly positioned blocks, a rectangular portion formed on said rod adjacent said vertical side walls, said notches to permit movement of a wrench applied to said portion and a spacing cover seated on said tie between the inner rail supporting blocks,

10 15 means for securing the same thereon and arms depending from said spacing plate adapted to straddle the rectangular portion of said rod to prevent rotary movement thereof whereby the rail supporting blocks 20 are held in adjusted positions.

2. A device of the class described comprising a rail tie of channel formation including side walls, end walls and a bottom wall, the inner faces of the side walls being upwardly and inwardly inclined from the bottom wall, the central portions of the inclined faces of the side walls being vertically disposed with notches formed therein, rail supporting blocks having angularly disposed

25 30 35 40 45 50 55 60 side walls received in said channel tie through the central portion thereof and moved to a position whereby the inclined side walls thereof engage the inclined inner faces of the tie walls, enlarged heads carried by the rail supporting blocks, said blocks being cut away on their opposed faces adjacent said heads, dove-tail sockets formed in the upper sides of said cut away portions, cushion blocks received in said dove-tail sockets, rail engaging flanges carried by the blocks, a screw passing through each end wall of said tie adapted to engage the outer faces of the outwardly positioned blocks, a rod having threaded engagement with one of said inwardly positioned blocks and a loose engagement with the other one of said inwardly positioned blocks, a rectangular portion formed on said rod adjacent said vertical side walls, said notches to permit movement of a wrench applied to said portion and a spacing cover seated on said tie between the inner rail supporting blocks, means for securing the same thereon and arms depending from said spacing plate adapted to straddle the rectangular portion of said rod to prevent rotary movement thereof whereby the rail supporting blocks are held in adjusted positions, and rails positioned on said cushion blocks beneath the flanges carried by the supporting blocks, the upper edges of the side walls of the tie being cut away whereby the rails are slightly spaced therefrom.

3 A rail tie and support comprising a tie

member of channel formation, the opposed inner walls of the tie being inclined inwardly and upwardly, the central portion of the inner faces of the walls of the tie being vertical, rail supporting blocks having side walls angularly disposed and adapted for reception in said channel tie through the central portion thereof and subsequently moved to cause the side walls thereof to engage the inclined inner faces of the side walls of the tie, independent adjusting means for the outwardly positioned rail supporting blocks, a single element for simultaneously adjusting the inwardly positioned blocks and means engaging the single element to hold the same in adjusted position.

4. A device of the class described comprising a channel tie, rail supporting blocks slidably mounted therein and interlocked therewith, rails supported on said blocks, independent adjusting means for the outwardly positioned blocks, a single element for simultaneously adjusting the inwardly positioned blocks, and means associated with the single element for holding the same in adjusted position.

5. A device of the class described comprising a channel tie, sliding blocks interlocked therewith, cushion means carried by said blocks for supporting a rail in spaced relation to said tie, independent adjusting means for the outwardly positioned blocks and means for simultaneously adjusting the inwardly positioned blocks.

6. A device of the class described comprising a channel tie, rail supporting blocks 100 slidably disposed therein and interlocked therewith, the outwardly positioned blocks being independently adjustable, means for simultaneously adjusting the inwardly positioned blocks having threaded engagement 105 with one of said blocks and a loose engagement with the other of said blocks, and means for holding the simultaneously adjusting means in fixed position.

7. A device of the class described comprising a rail tie of channel formation, rail supporting blocks slidably disposed therein and interlocked therewith, independent adjusting means for the outwardly positioned blocks, means for simultaneously adjusting the inwardly positioned blocks, a spacing plate mounted on the upper edges of said channel tie between said inwardly positioned blocks, and cooperating means carried by the spacing plate and the adjusting means for the inwardly positioned blocks for holding the adjusting means and the inwardly positioned blocks in fixed position.

8. A device of the class described comprising a tie of channel formation, sliding 125 rail supporting blocks arranged therein and interlocked therewith, independent adjust-

ing means for the outwardly positioned blocks, one of the inwardly positioned blocks having a threaded opening therein while the other one has a socket therein, a rod having 5 a threaded end for engagement with the threaded opening and a plane end for reception in said socket, a spacing plate supported on said tie between the inwardly

positioned blocks and coöperating means carried by said plate and rod for holding the inwardly positioned blocks in adjusted 10 positions.

In testimony whereof we affix our signatures.

IVAN HANKOVICH.
WINKO HANKOVICH.
